UNITED STATES PATENT OFFICE.

MANUEL BRETOS Y CLAVERIA, OF SANTIAGO, CUBA.

SHUTTER APPLICABLE TO ALL KINDS OF FOLDING DOORS.

1,413,895.

Specification of Letters Patent. Patented Apr. 25, 1922.

Application filed July 26, 1920. Serial No. 399,155.

To all whom it may concern:

Be it known that I, MANUEL BRETOS Y CLAVERIA, a subject of the King of Spain, residing at No. 22 Gallo Street, Santiago, 5 Cuba, have invented a new and useful Shutter Applicable to All Kinds of Folding Doors, of which the following is a specification.

By means of my invention I secure a remarkable advantage in folding doors, such as providing them with a shutter, which by means of a very rapid and simple operation, may be opened and closed.

I also construct this shutter of jointed plates or sections which are extremely light.

Another advantage consists in the fact that the shutter is rolled up on being taken off, and without the disadvantage, as it happens with the shutters now in use, that being of a separable body, they have to be placed aside after they have been used, an operation which is quite troublesome.

Other advantages and purposes of the invention will be understood in the course of this description, the illustrative drawings of which represent:—

Fig. 1 is a general view of the door showing the shutter in a half closed position.

Fig. 2 is a view of the shutter already 30 rolled on its reel and of the door in position to be folded after the tracks, their annexes, and the bushing guide and safety bar have been folded.

Fig. 3 is a view of the shutter closed at 35 its outer face.

Fig. 4 is a general view of the drum of the shutter's reel.

Fig. 5 is a section through A—B, of the previous figure.

Fig. 6 is a detail view of the universal joint.

Fig. 7 is a side view of the same.

Fig. 8 is a section through C—D, of Fig. 7.

45 In the drawings, 2 indicates a shutter the constitution of which is the jointed or rolled system which is the subject matter of my application of the 26th of July, 1920, Serial No. 399,157, as this system is preferably used in this case. The shutter 2 is rolled up at its upper part on the reel 1 placed between the two drums 15. These drums are formed by the hollow cylinders 19 in their interior 18, as shown in Fig. 5, and rotate 50 around the axle box 32 which fits in the axle 3' of the door 20. The drums 15 complete a one piece casting or stamped iron, the

cases of sockets of the rollers 36 which contain the friction rollers 35, which are kept in position by means of the washer 34.

60 The axle box 32 is secured to the nut 37 screw threaded at its end.

As arrangements substantially the same as those of ordinary doors, I here illustrate the drums of the door 16, the supporting 65 means 14 of the axle 3' of the door and through 17, the tracks of that door.

The shutter is limited to the section indicated in 2 which covers the door-hole 4, starting from line 25.

70 In 13, are shown braces which are rolled up in the reel 15, from which braces hang the shutter which is also rolled in said reel, as shown at 1', Fig. 2. At the door sill and over its threshold is arranged the guiding 75 bar 10, supported by bracket 11.

This bar is provided at 9 with a set of universal joints from which are connected the U-shaped section tracks 6 situated in an inverse position, as indicated in Fig. 8. Of 80 the U track which has the larger flange 26, engaging the edge of the door-hole 4 which must cover the shutter 20 like a frame, while the other adjacent U, 27, serves as a guide for the shutter.

85 The set of universal joints 9, hinges at 28 with the track, and in turn joins at 29 the sliding standard or pedestal along the guiding bar 10.

A plate 31 closes the track double U of 90 the double guide at each side of the door hole and at that plate in 38 are jointed the strengthening or safety bars 5, the joint of which only permits the side rotation or movement of said bars. These bars are 95 placed parallel to the tracks 6 and are transversely secured to the latter by means of the latches 7, and are rigidly maintained clamped to the door by means of the pins 8 and enter by a strong friction under the 100 bridges 3 at the height of the top piece of the shutter.

At 12 are indicated some pieces to support the tracks and safety bars on being folded.

105 The operation necessary to open and close this shutter is rapid and simple.

Once they are rolled up in the position shown in Fig. 2, that is to say, when the door is in the lower position, it will be sufficient to take out tracks 6, causing the same 110 to rotate on the set of joints 9, and inserting them through U 26 in the edges of the hole 4; then the safety bars 5 are raised and arranged around the joint 38 and said bars

are secured and are passed under the bridges 3 and the latches and clamps 7 and 8 are properly adjusted. Then the shutter 2 hanging from the folding braces 13 is pulled 5 and slides until it is placed between the tracks 27.

Whenever it is desired to raise the shutter, said shutter is pushed upwards, said impulse being accompanied by a hook or a 10 similar device, and as soon as it is rolled up the latches and clamps are disconnected from the safety bars and the tracks, the former sliding out the bridges 3 and rotating laterally; then the frame tracks are 15 taken out of the edges of the door-hole and rotate in a facing position around the universal joint set 9, carrying along with its, the plate 31 which carries the bars 5, folding both the tracks and bars in the position 20 indicated in Fig. 2.

It is evident that slight modifications can be made in everything that has been set forth, provided no alteration is made in the fundamental object of the invention, as 25 stated below:—

What I claim is:—

1. In flexible doors, the combination of a large flexible door having an opening therein, and a flexible door slidably engaged in 30 said opening.

2. In flexible doors, the combination of a large flexible door having an opening therein, guides at said opening, and a door slidably engaged in said guides, said guides being 35 removable from said opening to allow said large door to be flexed when raised.

3. In flexible doors, the combination of a large flexible door having an opening therein, guide strips at said opening, a small door 40 slidably engaged in said strips, said guide strips being removable from said opening, and clamps adjacent said opening for receiving and holding said guide strips when supporting said small door.

4. In flexible doors, the combination of a large flexible door having an opening therein, guideways at said opening, and a small door slidably engaged in said guideways, said guideways being attached for folding 50 away from said door opening and carried by said large shutter.

5. In flexible doors, the combination of a large flexible door having an opening therein, guideways at said opening, and a small door slidably engaged in said guideways, said guideways being attached for folding away from said door opening and carried by the lower transverse edge of 55 said large door.

6. In flexible doors, the combination of a large flexible door having an opening therein, guideways at said opening, a small flexible door to slide in said guideways, transverse rods at the lower end of said 60 large door, brackets slidable upon said rods

and pivotally connected to said guides for allowing said guides to be folded at the lower edge of said large door.

7. In flexible doors, the combination of a large flexible door having an opening therein, guide strips at said opening consisting in cross section of a pair of U-shaped portions one inverted to the other, and a small door slidably engaged in one of the U-portions of each strip, the U-portions inverted 75 to the first mentioned receiving the edges of the opening.

8. In flexible doors, the combination of a large flexible door having an opening therein, a second flexible door slidably engaged 80 in said opening, and means for raising said last mentioned door.

9. In flexible doors, the combination of a large flexible door having an opening therein, a second flexible door slidably engaged 85 in said opening, and rollers for winding said doors thereupon.

10. In flexible doors, the combination of a large flexible door having an opening therein, a second flexible door arranged to slide 90 over said opening, a transverse shaft, rollers fixed to said shaft for winding said large flexible door, and a roller loose upon said shaft for winding said second mentioned flexible door.

11. In flexible doors, the combination of a large flexible door having an opening therein, a second flexible door arranged to slide over said opening, a transverse shaft, rollers fixed to said shaft for winding said large 100 flexible door, a roller loose upon said shaft, and straps connecting said second mentioned flexible door to said loose roller.

12. In flexible doors, the combination of a large flexible door having an opening therein, a second flexible door arranged to slide over said opening, a transverse shaft, rollers fixed to said shaft for winding said large flexible door, an elongated roller loose upon said shaft having flanges at its ends, said 110 elongated roller being adapted for winding said second mentioned flexible door, said fixed rollers and said flanges of said loose roller being adapted for winding said first mentioned flexible door.

13. In flexible doors, the combination of a large flexible door having an opening therein, a second flexible door arranged to slide over said opening, a transverse shaft, rollers fixed to said shaft for winding said large 120 flexible door, an elongated roller loose upon said shaft having flanges or roller portions at its ends, said elongated roller portions being adapted for winding said second mentioned flexible door, said second mentioned 125 portion serving as a roller together with the fixed roller for winding said first mentioned door.

In witness whereof I affix my signature.

MANUEL BRETO'S y CLAVERIA.
